INVENTOR

BY
W. H. Miller.

ATTORNEY,

UNITED STATES PATENT OFFICE.

JOHN M. AKERS, OF ALLIANCE, OHIO.

STORE-SERVICE APPARATUS.

SPECIFICATION forming part of Letters Patent No. 392,771, dated November 13, 1888.

Application filed March 27, 1888. Serial No. 268,686. (No model.)

To all whom it may concern:

Be it known that I, JOHN M. AKERS, a citizen of the United States, and a resident of Alliance, county of Stark, State of Ohio, have invented a new and useful Improvement in Store-Service Apparatus, of which the following is a full, clear, and exact description, reference being had to the accompanying drawings, making part of this specification.

10 My invention relates to improvements in store-service apparatus; and it consists in providing means, as hereinafter described, for securing the apparatus in working position and to impart initial impetus to the carriers, and 15 to the detail and combination of parts, as set forth in the claims.

Figure 1 is a side elevation of store-service apparatus illustrating my invention secured to a counter or below the wireway. Fig. 2 is same 20 view, showing service supported from the ceiling or above the wireway, partly sectional. Fig. 3 is a sectional view of detail, hereinafter explained; and Fig. 4, a key for tightening the wireway.

25 A represents a hollow post having a base, B, by which it may be secured to a counter or ceiling, and a set-screw, a, by which the adjustable stem C may be secured in desired adjustment therein. On the outer end of said stem there 30 is mounted a hollow body portion, D, having on one of its ends a head, b, through which there is provided a central perforation, c, that is smaller than the annular bore d of the body D. In the body portion D is placed a coil-spring, 35 E, one end of which rests against the head b, through which is passed the rod F, said rod having one end enlarged, as f, forming a piston, which fills the annular bore of the body D, and a shoulder, g, to rest against the end of the 40 spring E, substantially as shown in Fig. 2.

On the inner end of the rod F is secured an open-ended mouth-piece, G, in which is pivotally secured the clamping-jaws h, said jaws having near their free ends shoulders i, and are 45 moved inwardly by the exertion of the spring j and outwardly by the cam k, secured to cross-pin l, which is journaled in the side of the mouth-piece G. On the outer end of said pin is mounted a trip-lever, m, and on the outer 50 portion of the rod F is secured a catch, n, and a rubber buffer, o, hereinafter explained.

From the body D there is projected an arm, H, as shown, to the free end of which is pivotally secured a hand-lever, J, said lever having a through-mortise, p, through which the 55 rod F is passed, and a handle portion, q.

To the side of the lever J there is pivotally secured a gravity-actuated pawl, K, in the form of a bell-crank, as shown in Fig. 1, having on its upper inner end a catch, r, and to the lower 60 portion links s s, by which said pawl is connected to the body portion D, the length of said links or their equivalents being adapted to the desired movement of the rod F. The lever J is connected to the arm m by the chain 65 L, the object of which will be hereinafter explained.

On the under side of the body D there is provided an arm, M, having in its outer end a perforation, t, through which the end of the wireway N is passed, and at its inner end a turn-pin, u, about which the wire may be wound by the use of the key O, and held tight by the rack-wheel v, mounted on said pin and pawl w.

Two sets of the hereinbefore-described apparatus are required for each line of service, one of which is placed at the cash-stand and the other at any desired point in the store, and connected by a single wireway, N, made tight by the means hereinbefore described. A carrier, P, of the form substantially as shown in Fig. 1, is provided, having a frame, a', wheels b', depending cup-support c', cup d', conical catches f', and rubber buffers g'. The cup d' may be removed by pressing in the spring- 85 buttons h'.

To adapt the apparatus for a depending connection with the ceiling of the room, the stem C may project from the upper side of the body D, as shown in Fig. 2, and the standard A inverted to form a hanger for the apparatus. This send-off is so constructed as to be moved or controlled by the operator in one direction to compress the spring, and by the energy of the spring in the other direction to impart a 95 forcible and sudden movement to the carrier upon the way, and is operated as follows:

The conical head or catch of the car is passed into the jaws on the driving-rod, and the hand-lever pressed in until the pawl drops into the 100 catch on the rod. The lever J is then drawn back, compressing the spring E to a certain

distance, limited by the links *S*, which, when straight, raise the pawl (see Fig. 2) out of engagement with the catch, releasing the spring which drives the rod out. The chain *L*, becoming tight before the movement of the rod is arrested by the buffer *o*, draws the lever *m* in, as shown in Fig. 3, and the cam *k* so turned as to spread or open the jaws *h* and release the car, which, having received the impulse of the spring, is driven over the wireway to the station, where it is caught in the jaws *h*, the motion of the car being arrested by the yielding of the spring *E* without injurious jar or noise. Thus the car is sent back and forth over the wireway, regardless of grades, with great rapidity and certainty.

Having thus fully described the nature and object of my invention, what I claim, and desire to secure by Letters Patent, is—

- 20 1. The combination, with the way and carrier, of the supporting-stem having a hollow portion, a spring located therein, a piston or driving rod operated by said spring, jaws to secure the carrier to the rod, a catch, as *n*, on said rod, a hand-lever, *J*, pawl *K*, pivoted thereto and adapted to engage the catch *n*, links pivoted to the frame, and the hand-lever whereby the rod or piston is released when the links become substantially in a line with each
- 25 30 other, substantially as set forth.

2. The combination, with the way and car-

rier, of a supporting-stem, a hollow body portion inclosing a spring-actuated piston or driving rod, jaws pivoted to said driving-rod, a lever for retracting said driving-rod, and a cam located between said jaws and connected to the lever, substantially as set forth. 35

3. The combination, with the way and the carrier, of the supporting-stem, a hollow body portion inclosing a spring-actuated piston or driving rod, a catch secured at one end of said driving-rod and pivoted jaws at the other end, a cam located between said jaws, a hand-lever, a pawl pivoted thereto, links pivoted to said pawl and to the frame or post, and a cord or 40 chain connected to the said cam and to the lever, substantially as set forth. 45

4. The combination, with the way and the carrier, of the supporting-stem, a hollow body portion inclosing a spring-actuated piston or 50 driving rod, jaws pivoted thereto, a spring engaging said jaws, a cam located between the jaws, a lever, and a chain or cord connecting the cam therewith, whereby when the driving-rod is retracted the pivoted jaws will be spread 55 apart, substantially as set forth.

In testimony whereof I have hereunto set my hand this 22d day of March, A. D. 1888.

JOHN M. AKERS.
